RADIATOR

Application filed September 11, 1931. Serial No. 562,306.

This invention relates generally to heating radiators and particularly to unitary cabinet-type radiators which may be set in the wall of a room.

Heretofore radiators have been set in or concealed within the walls of a room by providing separate cabinets or housings within the walls for receiving narrow radiators. Ordinarily each housing is built into the wall to constitute an air passage having inlet and outlet openings, and the radiator is suspended or mounted within the housing thus constructed.

It is an object of the invention to provide an inset radiator having the housing and the heating unit combined to constitute a unitary structure. A further object of the invention is to provide a concealed radiator of compact and rugged structure, so designed that it will be sanitary and easily cleaned.

In accordance with this invention, a radiating structure is provided having a heating element, preferably a tube of copper, on which is mounted a cabinet structure made up of a plurality of independent sections. The sections are fastened together in such manner that the entire radiator constitutes a unitary article of manufacture which may be readily installed in a wall. Each section constitutes an individual flue having inlet and outlet openings shaped to conform to the air stream to conduct air through the radiator and shaped to avoid collecting dirt. The sections are so mounted on the tube that they are heated by conduction from the tube and function as extended surfaces for heating the air that passes through them.

The stated objects of the invention, and others that will become apparent upon further consideration of this specification, may be achieved by the apparatus described herein and shown in the accompanying drawings, in which

Fig. 1 is a view in elevation of a radiator embodying our invention set in the wall of a room;

Fig. 2 is a view in vertical section of the radiator shown in Fig. 1 taken on the plane represented by the line II-II;

Fig. 3 is a view in section, similar to Fig. 2 showing a somewhat modified construction; Fig. 4 is a view, similar to Fig. 2, of another modification;

Fig. 5 is a view, similar to Fig. 2, of a further modification;

Fig. 6 is a view in perspective of a radiator section similar to, but constituting a modification of, the sections of the radiator shown in Fig. 1;

Fig. 7 is a view in horizontal section of a portion of the radiator taken on the line VII-VII of Fig. 2;

Fig. 8 is a view in front elevation of a modified type of radiator embodying our invention;

Fig. 9 is a view in end elevation of the radiator shown in Fig. 8;

Fig. 10 is a view in vertical section of a portion of the radiator taken on the plane represented by the line X-X of Fig. 8;

Fig. 11 is a view in horizontal section of a portion of the radiator shown in Fig. 8 taken on the plane represented by the line XI-XI;

Fig. 12 is a view in perspective of a section similar to but constituting a modification of the sections of the radiator shown in Fig. 8; and

Fig. 13 is a view in perspective of another section similar to those of the radiator shown in Fig. 8.

Referring more particularly to the drawings, the radiator constructed in accordance with this invention is adapted to be set in the wall 1 of a room, as shown in Fig. 1, with most of its structure concealed from view. When installed in this manner in the wall, the radiator does not occupy floor space, or other useful space, and it may be adapted to readily conform to the decorative scheme of the room.

The radiator is provided with an air inlet opening 2 that is ordinarily disposed near the floor. In this particular structure it is shown just above a base-board 3. Air entering the inlet opening 2 passes upward through the radiator within the wall 1 and returns to the room, after being heated, through an outlet opening 4 near the top of 100

the radiator, similar in appearance to the inlet opening 2, and disposed, in this instance, for convenience, just below a sill 5 of a window. The surface between the inlet opening 2 and the outlet opening 4 constitutes a portion of the wall 1 that may be covered by plaster and paper, or other suitable surface material, in the same manner that the remainder of the wall is covered.

10 With the radiator set in the wall in this manner, the only portions exposed to view are the inlet and outlet openings, and an operating handle 8 for controlling the supply of heated fluid to the radiator.

15 The radiator shown in Fig. 8 differs somewhat from that shown in Fig. 1 in certain details but in general embodies the same principles and functions in the same manner. Inasmuch as the radiator shown in Fig. 8 20 is not installed in the wall of a building, it shows somewhat more in detail the elements which go to make up the structure and will therefore be described first.

As shown in dotted lines, the heating 25 element of the radiator comprises one or more horizontally disposed runs or tubes 9, positioned one above the other and connected together at their ends to constitute a single continuous passageway for conveying 30 through the radiator a heated fluid which may be steam, hot water, or any other suitable heat-transferring medium.

The body portion of the radiator is made up of a plurality of sections 11 mounted on 35 the tubes 9 in such manner that each section is heated by conduction from the heating element. Also each section constitutes an individual flue for drawing air over the heating elements 9. Air within the sections 40 is heated not only directly from the tubes 9 but also from the heated interior surfaces of the sections. The heated air tends to rise and to set up convection currents through 45 the radiator that cause air from the room to be drawn in through the inlet opening 2, and 50 expelled through the outlet opening 4 after being heated. Such surfaces of the sections that may be exposed, also function as radiating surfaces for radiating heat directly 55 into the room.

As shown in perspective in Fig. 13, each 60 section 11 comprises a side wall or transverse plate 12 provided with spaced openings 13 disposed to engage the horizontal tubes 9. At the front of the section there is formed an integral front plate 14 which in the modification of the invention shown in Figs. 8, 9 and 10 may constitute a portion 65 of an exposed front panel that occupies the space between the inlet and outlet openings in the completed radiator and functions as an active radiating surface. The front plate 14 is shorter than the side plate 12 by the amount necessary to provide the inlet 70 and outlet openings 2 and 4, respectively.

The back of the section is formed by an integral back plate 15 that extends parallel to the front plate 14 throughout its mid-portion, and is curved forward at its upper and lower portions to bring its ends in line 70 with the ends of the side plate 12 at its forward edge, whereby the ends of the back plate constitute the bottom and top, respectively, of the opening 2 and the opening 4.

The section shown in Fig. 13 is similar 75 to the section of the radiator shown in Figs. 8, 9 and 10 with the exception that it is recessed. That is, the front plate 14^a is set back to provide room for applying wall covering over it in the manner shown in Fig. 1.

The front wall may be made continuous from the top to the bottom of the section as shown by the wall 14^b of the section 11^b in Fig. 12. In this modification the front wall and the back plate constitute a continuous strip or ribbon around the section, and inlet and outlet openings 2^b and 4^b, respectively, are punched in the front wall at suitable positions near the bottom and top 80 as shown.

The curved shape of the upper and lower portions of the section conforms to the normal air stream and thus assists circulation of air through the section.

To further increase the area of the heated metal to which air is exposed within the radiator, a plurality of free intermediate plates 17 may be mounted on the tubes 9 within each section. As shown in Fig. 10 90 these plates are somewhat narrower than the side plates 12 of the section and are substantially equal in height to the front plate 14, but they may be made in any convenient size and shape. The intermediate plates 17 and the sections 11 may be manufactured by 95 stamping or pressing them from any suitable sheet metal, as for instance from an inexpensive grade of sheet steel.

In assembling the radiator, the sections 11 are placed in juxtaposition with the side 100 wall 12 of each section constituting a partition between it and the next section, and with the required number of free plates 17 disposed within each section. The sections and plates may be held in position by any suitable fixture and the upper and middle runs of horizontal tubing 9 passed through 115 the openings in the transverse plates 12 and intermediate plates 17.

The tubes 9 are preferably of drawn copper and the upper and middle runs are formed from a single piece of tubing by bending it upon itself with the proper degree of curvature to provide parallel horizontal runs spaced to fit the spaced holes 13 120 in the transverse plates 12.

The lower run of the tube 9 is a simple straight piece of tubing which is inserted through the lower openings 13 in the sections and joined to the middle run by a 130

suitable bend or elbow connection 19 that, as here shown, may be fastened to the tubes by compression couplings 20.

No intermediate plates are provided in the 5 end sections inasmuch as the space is occupied by the tube bends. The ends of the radiator may be closed by suitable end plates 21 that may be pressed into engagement with the edges of the end sections.

10 After the radiator has been assembled, it may be rigidly locked together by soldering or galvanizing the entire structure, or the tubes 9 may be expanded by hydraulic pressure to grip the plates and sections carried 15 by them. When thus assembled and locked together, the radiator constitutes a rigid unitary structure which may be mounted in the wall of a room without the necessity of providing any additional casing or housing 20 for receiving it.

As shown in Figs. 2, 6 and 7, the detailed construction of the radiator, shown generally in Fig. 1, is quite similar to that shown 25 in Fig. 8, with the exception that a larger number of main transverse plates are utilized and the intermediate plates 17 are entirely dispensed with. The heating medium is conducted through horizontal runs 30 of pipes 9 connected together to constitute a continuous passageway in the same manner that the tubes 9 shown in Fig. 8 are connected. On the pipes 9 are mounted a plurality of transverse plates 22 having flanged pipe-receiving openings 13, each of which 35 constitutes a partition for dividing the radiator into a plurality of independent flues for convection currents of air. The flanges of the pipe-receiving openings 13 are in heat-conducting contact with the pipes 9 40 and transmit heat to the transverse plates 22 which, in turn, assist in heating the air in the radiator.

At the front edge of each transverse plate 22 there is an integrally formed front plate 45 24 which, in the modification shown in Figs. 1 and 2, is set back or depressed from the plane of the openings 2 and 4 a sufficient distance to permit wall covering such as plaster 23 to be applied across the front of 50 the radiator. Instead of plaster, a decorative metal panel may be used to enclose the front of the radiator, or other suitable covering may be applied.

As shown, the front plate 24 is shorter 55 than the transverse plate 22 and is disposed at the mid-portion thereof to provide openings above and below it that constitute the air inlet and outlet openings 2 and 4 respectively. A back plate 25 is disposed 60 parallel with the front plate 24 throughout its mid-portion and is curved forward at its upper and lower portions. The upper and lower ends of the back plate 25 are then turned outward to form an S-curve 65 which brings them into the plane of the

front plate 24 in such manner that they constitute flanges at the top and bottom of the radiator by means of which the unitary structure may be attached to the wall of a building, as shown in Fig. 2. The curved back plate 25 gives a stream-line effect to the air passage through the section and thus provides a path of low resistance for the convection currents.

The section shown in perspective in Fig. 6 is similar to the sections that make up the radiator shown in Figs. 1 and 2, with the exception that the front plate 24^a is not set back. In this modification, the front plate 24^a is disposed in the plane of the openings 2 and 4 and occupies the space taken by the wall covering 23 shown in Fig. 2. When the radiator is constructed with sections of this type, the front wall 24 radiates heat directly to the room.

In the modification shown in Fig. 3, the radiator is constructed in much the same manner as that shown in Figs. 1 and 2. However, in this structure, the back plate 25^b of each section and the transverse plate 22^b are cut off even with the lower end of the front plate 24^b leaving the bottom of the radiator open. A suitable grill member 31 may be mounted in an opening in the base board 3 to cover the air inlet opening for 95 this radiator.

The radiator shown in Fig. 4 is another modification in which the back plate 25^c of each section is carried forward at the lower end, as in the radiator in Fig. 2, but extends upward without curvature. The front plate 24^c extends upward also to the level of the upper end of the back plate thus providing an outlet opening in the top of the radiator and maintaining the front of the radiator closed. As shown in the drawings, the inlet opening 2^c is formed in the base board 3 and the outlet opening of the radiator communicates with a horizontally disposed grill 32 in the top of a shelf or sill 33 above the radiator. This particular structure is shown with five horizontal runs of tubing.

In the event that the radiator is to be used for heating air brought into a room from out-of-doors, or from an air well in the wall, it may be constructed as shown in Fig. 5. In this structure the back plate 25^d is curved forward at the top and is terminated at the bottom just below the lower run 115 of the pipe 9 as in the modification shown in Fig. 3. The outlet opening 4 is provided in the forward face of the radiator near the top in the usual manner. For admitting air from the rear an inlet opening 33 is provided in the outer surface of the wall 1 at the bottom of the radiator. To form a streamline air passage from the inlet opening 33 into the radiator the front plate 24^d is extended downward and curved rearward 120 125 130

to place its end in the plane of the back plate 25^a. Four runs of pipe 9 are shown in this modification of the invention.

The radiators shown in Figs. 1 to 5 may be assembled in much the same manner that the radiator shown in Fig. 8 is put together, with the exception that no intermediate plates are placed within the sections.

As shown in Fig. 7, the tubes 9 are passed through the tube-receiving openings 23 in the transverse plates 22, in such manner that the front and back plates form a continuous outer shell or cabinet for the radiator. After the transverse plates 22 have been mounted on the tubes 9 the structure may be rigidly secured together, as by expanding the tube 9 to grip the flanges of the openings 23, by a soldering, or other suitable connecting process.

Suitable end plates may be applied in any convenient manner to enclose the bends of the tubes 9 or the tube bends may simply be uncovered and hidden from view. The unitary structure may then be mounted in a recess in the wall of a room as shown.

After being thus mounted, the usual supply and return pipes may be connected to the tubes 9 and the plaster or other wall covering applied either directly to the front plates 24 or supported on a suitable structure spaced from the plates 24. The appearance of the finished heating unit may be enhanced by applying a suitable beading or border 35, that may be of polished metal or other suitable material, around the inlet and outlet openings.

As shown in Fig. 1, the exposed edges of the transverse plates 22 constitute in themselves a decorative grill and prevent to a large extent, viewing of the interior of the radiator. If it is desirable, any well known type of decorative grill structure may be applied to the inlet and outlet openings in the same manner that such grills are now applied to air outlet openings for admitting heated air to a room from recessed or concealed radiators.

In Fig. 1 a covered front panel is applied to one modification of the invention, and in Fig. 8 an exposed radiating panel is shown on another modification, but it will be understood that either of these and other modifications may be utilized with either the exposed radiating front panel or with the recessed panel covered by the wall covering which is applied to the walls of the room. Any convenient number of runs of tubing may be used in any modification. Also it will be understood by those skilled in the art to which this invention relates that various other modifications may be made in the structures embodying the invention without departing from the spirit and scope of the invention defined in the appended claims.

65 We claim:

1. A heating radiator adapted to be set in a wall, comprising a horizontally disposed tube, and a plurality of box-like elements, carried by the tube, having vertical faces and curved backs and having air inlet and outlet openings in the vertical faces. 70

2. A heating radiator adapted to be set in a wall, comprising a horizontally disposed tube for heated fluid, a plurality of box-like elements mounted on the tube, said elements having vertical faces with air inlet and outlet openings, and means for supporting the structure in a wall of a room to be heated with the inlet and outlet openings substantially flush with the surface of the wall. 75

3. A heating radiator comprising tubing for conducting heated fluid, and a plurality of box-like elements mounted on and enclosing the tubing, said elements having vertical faces with inlet and outlet openings near the bottoms and tops of the faces, and vertical backs having curved end portions that constitute the bottoms and tops of the elements. 80

4. A heating radiator comprising tubing for conducting heated fluid, a plurality of box-like elements mounted on and enclosing the tubing, said elements having vertical faces with inlet and outlet openings near the bottoms and tops, respectively, thereof, and vertical backs having curved end portions that constitute the bottoms and tops of the elements, said backs and their curved ends constituting a continuous wall for guiding air from the inlet openings to the outlet openings. 90

5. A heating radiator comprising tubing for conducting heated fluid, a plurality of box-like elements mounted on and enclosing the tubing, said elements having vertical faces with inlet and outlet openings near the bottoms and tops, respectively, thereof, and vertical backs having curved end portions that constitute the bottoms and tops of the elements, said backs and their curved ends constituting a continuous wall for guiding air from the inlet openings to the outlet openings, and vertical plates carried by the tubing within each element for transferring heat to the air passing through the radiator. 105

6. A radiator comprising a plurality of box-like elements placed in juxtaposition and having aligned openings, said elements each comprising one side wall, a back wall forwardly curved at its upper end from the front top edge of the side wall, and a vertical front wall having air inlet and outlet openings to constitute a series of curved flues, and tubing extending through the openings in the elements holding them together and having heat-conducting contact with each element. 110

7. A radiator comprising a plurality of box-like elements placed in juxtaposition, said elements each comprising one side wall 115

- having tube-receiving openings, a curved back wall extending from the front top edge of the side wall to the front bottom edge thereof, and a vertical front wall having 5 passageways near the top and bottom of the element, tubing extending through the openings in the elements holding them together to constitute a series of curved flues having inlet and outlet passageways adjacent the 10 ends of and in the plane of the front wall, and vertical plates within the elements mounted on the tubing to conduct heat therefrom to the air.
8. A heating radiator adapted to be set 15 in a wall, comprising a horizontally disposed tubular heating element and a plurality of vertical sections in heat-conducting contact with said heating element, said sections having their edges formed at right angles to 20 the main surface of the section to form a front, back, top and bottom inclosure around said heating element and having air inlet and outlet openings near the bottom and near the top thereof.
- 25 9. A heating radiator adapted to be set in a wall, comprising a horizontally disposed tubular heating element, and extended surface sections carried by the heating element, each of said sections including a transverse 30 plate in heat-conducting contact with the element, an integral front wall having inlet and outlet opening for air, and an integral back wall disposed parallel to the front wall at its mid-portion and curved forward at its 35 top and bottom portions to constitute a curved flue for convection currents of air.
10. A heating radiator for heating a room, comprising a plurality of sections set in the wall of the room, each of said sections including a transverse plate, an integral front plate disposed substantially in the plane of the wall surface exposed to the air of the room to permit emission of radiant heat and having air inlet and outlet openings, 40 and a back plate having forwardly curved ends forming a curved flue, and a horizontally disposed heating element passing through the transverse plates and having heat-conducting contact therewith.
- 45 11. A heating radiator comprising a plurality of sections set in the wall of a room, each of said sections including a transverse plate, a back plate, and a front plate disposed substantially in the plane of the wall 50 and exposed to permit direct emission of radiant heat to the room and having air inlet and outlet openings for permitting convection currents to flow through the radiator, and a heating element disposed in heat-conducting contact with the transverse plates.
- 55 12. A heating radiator comprising a plurality of sections adapted to be set in the wall of a room, each of said sections including a transverse plate, a back plate, and a front 60
- plate disposed substantially in the plane of the wall and exposed to permit emission of radiant heat to the room and having air inlets in the front wall and being open at the top to permit convection currents to flow 70 through the radiator, and a heating element disposed in heat-conducting contact with the transverse plates.
- 65 13. A heating radiator comprising a plurality of sections adapted to be set in the wall 75 of a room, each of said sections including a transverse plate, a back plate, and a front plate disposed substantially in the plane of the wall, open at the bottom and having air outlets in the front wall for permitting convection currents to flow through the radiator, and a heating element disposed in heat-conducting contact with the transverse plates.
- 80 14. An integral heating radiator adapted 85 to be built into the wall of a room with its front exposed and comprising a heating-fluid conducting-tube, a plurality of box-like cabinet-forming elements threaded on the tube in close-fitting engagement therewith and with 90 each other, said elements being made of sheet metal bent to provide integral front and back walls for the radiator and providing bottom and top openings to permit thermal circulation of air therethrough, one of said 95 openings being in the front wall of the radiator, the front wall of the radiator being directly connected to the tube through the integral transverse walls of the said sections.
- 98 In testimony whereof, we hereunto sign 100 our names.
